BODY TREATING APPARATUS

Harry L. Gordon, Sunland, Calif.

Application July 17, 1951, Serial No. 237,081

5 Claims. (Cl. 128—38)

1

My invention relates to and has for a purpose the provision of an apparatus which, by the user, is applicable to any part of the body and readily operated to relieve himself of pain resulting from subnormal blood circulation, through the application to the skin of heat in the presence or absence of a partial vacuum, whereby the circulation of blood in the area of the existing pain is sufficiently increased to relieve the user of pain in that area.

I will describe only one form of apparatus embodying my invention, and will then point out the novel features thereof in claims.

In the accompanying drawings:

Fig. 1 is a view showing in perspective one form of apparatus embodying my invention, as applied to the spine of the user.

Fig. 2 is an enlarged elevational view of the apparatus without the operating devices shown in Fig. 1.

Fig. 3 is a top plan view of the apparatus.

Fig. 4 is a view taken at right angles to Fig. 2.

Fig. 5 is a vertical sectional view taken on the line 5—5 of Fig. 4, showing the apparatus applied to the skin of the user and in one of the two positions which it is adapted to occupy.

Fig. 6 is a view similar to Fig. 5 showing the apparatus in the other position.

Fig. 7 is a sectional view on the line 7—7 of Fig. 5.

Fig. 8 is a sectional view on the line 8—8 of Fig. 6.

Fig. 9 is a detail perspective view of the nozzle shown in Figs. 5 and 6.

Referring specifically to the drawings my invention in its present embodiment comprises a body designated generally at B which may be constructed of metal or any other suitable material, and which is made up of a lower section 15 and an upper section 16, both sections being of annular form, and the upper section being telescopically received in the lower section.

The lower section 15 is provided in its lower end with an opening 17 bounded by an annular flange 18 which forms a seat for the lower end of a coiled spring 19. The upper section 16 is constructed at its lower end to provide an annular collar 20 and an annular shoulder 21. The upper end of the spring 19 is received within the collar and bears against the shoulder 21 so as to normally urge the section 16 upwardly to the position shown in Fig. 6.

The upper end of the lower section 15 is provided with an opening 22 in which the upper section is freely movable, and to provide between

2

the two sections an inlet for air to enter the section 15 from atmosphere when the upper section is in elevated position. In the lowered position of the section 16, an annular gasket 23 bears against an annular flange 24, bounding the opening 22 to form an airtight seal between the two sections and to thereby close the opening 22.

The lower end of the section 15 has secured thereto, by means of screws 25, a collar 26 which serves to attach the upper end 27a of a conical and corrugated cup 27 formed of rubber, to the lower end of the section 15. This collar also serves to secure a pair of ears 28 on the upper end of a nozzle 29, to the lower end of the section 15. This nozzle 29 is of tubular form and is provided at its lower end with a plurality of ports 30. The nozzle is provided with an annular groove 31 in which the upper end of a helical spring 32 is received to attach the spring to the nozzle. This spring is of conical form and covered with rubber 32a, its lower end being concentric to the cup 27 and normally coplanar with the lower end of the cup.

The upper section 16 is constructed to provide a chamber 33 and a pipe 34 axially of the chamber and depending from the section to be slidably received in the nozzle 29. Adjacent the lower end of the pipe a sealing ring 35 is carried to prevent leakage of air between the pipe and the nozzle. The upper end of the pipe 34 leads to a passage 36 in the upper section 16, and extended into this passage is a pipe 37 connected at its outer end to a hose 38 which leads to a suitable source (not shown) of heated air under pressure.

The section 16 is constructed to provide a pipe 39 which at one end communicates with the chamber 33, and at its other end with a hose 40 that is adapted to lead to a suction pump (not shown) for a purpose to be described herein-after.

As best shown in Figs. 2, 3 and 4, the lower section 15 is provided exteriorly thereof with a pair of diametrically disposed ears 41 in which the lower ends of a pair of posts 42 are secured. The upper ends of these posts are provided with heads 43. Similarly, the upper section 16 is provided exteriorly with a pair of diametrically opposed ears 44 which are slidable on the posts 42 to allow the section 16 to telescope within the section 15 and to limit upward movement of the section 16 under the urging action of the spring 19, it being understood that the ears 44 abut the heads 43 in limiting such movement.

A pair of eyes 45 are formed on each of the

ears 44, and in these eyes snap-hooks 46 are engaged to connect a pair of manipulating devices 47 to the section 16. These devices are shown as comprising elastic cords 48 connected to the snap-hooks 46 at one end and to two handle grips 49 at the other.

In the use of my apparatus, without the devices 47, the apparatus is applied to any area of the body in which pain exists resulting from subnormal blood circulation, so that the open end of the cup 27 covers and is in contact with the skin overlying that area. With the hoses 38 and 40 connected, respectively, to a source of heated air under pressure, and a suction pump, heated air will be supplied to the pipe 34 to be discharged into the cup through the nozzle ports 30, while a suction is produced in the pipe 39.

By the user now pressing axially on the section 16 in the direction of the section 15, the section 16 is first moved from the elevated or open position shown in Fig. 6 to the lowered or closed position shown in Fig. 5, wherein the gasket 23 abuts the flange 24 to close the opening 22. Further pressure on the section 16 forces the cup 27 firmly against the user's skin, indicated at 59, to seal the skin area covered by the cup against the escape of the heated air so that such air as emitted from the nozzle is discharged directly against the skin. Concurrently with pressing of the cup against the skin the large end of the spring 32 is forced against the skin for a purpose to be later described herein.

Now that both the opening 22 and the outer end of the cup 27 are closed against the egress of air to atmosphere, the suction created in the pipe 39 by the suction pump becomes effective to withdraw the air from the cup as delivered thereto from the nozzle 29. In order that the apparatus function as intended the suction produced in the cup must be of such a degree as to produce in the cup a partial vacuum of a degree sufficient to exert a pull or drawing action on the skin exposed within the cup. This action is opposed in part by the lower convolution of the spring 32, since it maintains the skin and flesh relatively flat therein to prevent the skin from being injured by the vacuum. (See Fig. 5.)

With the apparatus operating as described, the stream of heated air as discharged from the nozzle and against the skin functions not only to open the skin pores and thus relieve them of perspiration, but to stimulate the flow of blood in and beneath that and adjacent skin areas. Under the drawing action imposed on the skin by the partial vacuum created in the cup, blood circulation is further stimulated. The net result is that the user is almost instantly and completely relieved of any pain in and beneath that skin area caused by pressure on the nerves resulting from blood congestion.

In many instances a person may relieve himself of pain by use of the heated air alone and dispensing with the vacuum, since the air as continuously and directly applied to the skin at suitable temperatures operates to stimulate blood circulation to relieve congestion in any area of the body to which it is applied. When the vacuum is not used, the pipe 39 is disconnected from the hose 40 to provide an outlet through which the heated air can, after leaving the cup, be continuously exhausted to atmosphere.

The apparatus may be moved readily from place to place on the skin of the user by first relieving the section 16 of inward pressure so as to allow the spring 19 to move the section to

open position in which the opening 22 is opened to place the interior of the section 15 in communication with atmosphere to break the vacuum created in the cup 27 through the pipe 39. This 5 relieves the skin of any drawing action by the vacuum so that the cup can be shifted to any position without injury to the skin. Thus the apparatus can be applied to any part of the body where the hands of the user can hold the apparatus in position on the skin.

The manipulating devices 47 are designed for use of the apparatus on the back of the user's body, and particularly along the spine. With these devices applied to the section 16 as described, the user can, by extending the cords 48 beneath the arms (see Fig. 1) and placing them under tension by pushing forwardly on the handle grips 49, press the cup 27 against the skin, and by increasing the tension on the cords move the section 16 to closed position in relation to the opening 22, so that the heated air and vacuum will operate to stimulate the blood circulation along the spine and more particularly between and around the vertebrae.

Manifestly, the devices 47 can be manipulated to shift the apparatus from point to point along the spine or to any other position on the back of the user. Incident to such shifting, the cords 48 are relieved of tension to allow the section 16 to move to open position under the action of the spring 19 so that the vacuum in the cup 27 will be broken to permit such shifting without injury to the skin. The cords being elastic can be stretched to exercise the user's arms while the apparatus is applied, if so desired.

Although I have herein shown and described only one form of apparatus embodying my invention, it is to be understood that various changes and modifications may be made herein without departing from the spirit of my invention and the spirit and scope of the appended claims.

What I claim is:

1. An apparatus of the character described, including: a hollow body having a first section provided with an open inlet end and an open outlet end, and a second section telescoping in the first section to occupy one position in which it closes the inlet end and another position in which it opens the inlet end; means for urging the second section to the second mentioned position; a cup secured to and surrounding the outlet end of the first section; a nozzle fixed to the first section and disposed within the cup; a pipe fixed to the second section and telescoping in the nozzle; an inlet passage in the second section leading to the pipe and adapted for connection to a source of hot air under pressure; an outlet passage in the second section leading to the interior of the first section, and adapted for connection to a source of vacuum; and manually operable means for pressing the cup into contact with the skin, and moving the second section to close the inlet end of the first section.

2. An apparatus of the character described, including: a hollow body having a first section provided with an open inlet end and an open outlet end, and a second section telescoping in the first section to occupy one position in which it closes the inlet end and another position in which it opens the inlet end; means for urging the second section to the second mentioned position; a cup secured to and surrounding the outlet end of the first section; a nozzle fixed to the first section and disposed within the cup; a

pipe fixed to the second section and telescoping in the nozzle; an inlet passage in the second section leading to the pipe and adapted for connection to a source of hot air under pressure; an outlet passage in the second section leading to the interior of the first section, and adapted for connection to a source of vacuum; and handle-carrying cords connected to the second section at diametrically opposed points operable manually to press the cup into contact with a person's body and also to move the second section to close the inlet end of the first section against the urging action of said means.

3. An apparatus as embodied in claim 1, wherein a helical spring is secured to the nozzle and disposed within the cup.

4. An apparatus as embodied in claim 1, wherein a helical spring of cone form is fixed at its small end to the nozzle so that its large end is substantially coplanar with the outer end of the cup.

5. An apparatus of the character described, in-

cluding: a hollow body having a first section provided with an open inlet end and an open outlet end, and a second section telescoping in the first section to occupy one position in which it opens the inlet end, and another position in which it closes the inlet end; means for urging the second section to the first mentioned position; a cup secured to and surrounding the outlet end of the first section; a nozzle fixed to the first section and disposed within the cup; an inlet passage in the second section communicating with the nozzle and adapted for connection to a source of hot air under pressure; and an outlet passage in the second section leading to the interior of the first section.
